UNITED STATES PATENT OFFICE.

RODOLPHE CHRISTESEN, OF NEW BRITAIN, CONNECTICUT, ASSIGNOR TO THE RUSSELL & ERWIN MANUFACTURING COMPANY, OF SAME PLACE.

DESIGN FOR A FIRE-IRON STAND.

SPECIFICATION forming part of Design No. 13,101, dated August 1, 1882,

Application filed May 31, 1882. Term of patent 7 years.

To all whom it may concern:

Be it known that I, RODOLPHE CHRISTESEN, a citizen of the United States, residing at New Britain, in the county of Hartford and State of Connecticut, have invented and produced a new and original Design for Fire-Iron Stands, of which the following is a specification, reference being had to the accompanying photograph, forming part thereof.

10 A designates the base, of rectangular form, with tapering sides. Upon the upper edge, at the front and two ends of the base, there is a semicircular projection, as shown. Inside of the base, at the bottom, there is a sunken panel, 15 the surface of which is ornamented by a conventional plant, with the representation of a sunflower in the middle of the panel. Rising from the base, upon the back side, there is an arched brace, B, having a flat front face 20 ornamented in relief. Above the brace B is an ornament formed by two circular projections, b b, with an ornamented face, from which projections the upright extends. The cross-arm C is flat, with vertical edges, and its ends are curved, 25 so that the outer edge conforms to the contour of the two ends of an oval figure. At the middle of the cross-piece, upon the inside, there is a semicircular recess, a, as shown. The upper face of this cross-arm is ornamented as 30 may be desired. Surmounting the upright is the head or handle D, which is in the form of a four-sided prism, and upon the front face there is an ornament consisting of a conventional vase, plant, and sunflower.

35 The contours of the brace B, projections b b, and cross-piece C are supposed to be new independent of their particular ornamentation, and the ornamentation of the base and the

front of the head D is also believed to be new. Other features of ornamentation are also new; 40 but it is not desired to make any special claim to them.

I claim—

1. The design for a fire-iron stand herein shown and described, the same consisting of 45 the rectangular base having flaring sides, with the semicircular projections upon the upper edge of the ends and front, and a panel upon the inside, at the bottom, ornamented by a conventional plant and sunflower.

2. The design for a fire-iron stand herein shown and described, the same consisting of a base, arched brace having a flat front face ornamented in relief, the circular projections b b, just above said arched brace, and the up- 55 right extending from said projections.

3. The design for a fire-iron stand herein shown and described, the same consisting of the cross-piece having the semicircular recess a at the middle of its front.

4. The design for a fire-iron stand herein shown and described, the same consisting of the cross-piece C, having the flat upper and lower faces, the vertical edges, and curved ends conforming to the contour of the two ends of 65 an oval figure.

5. The design for a fire-iron stand herein shown and described, the same consisting of the head in the form of a four-sided prism, with its front face ornamented by a conventional 70 vase, plant, and sunflower.

RODOLPHE CHRISTESEN.
